SHOE

William H. Goodyear, Carlisle, Pa., assignor to
G. E. Kinney Co., Inc., New York, N. Y., a cor-
poration of New York

Application August 11, 1936, Serial No. 95,403

2 Claims. (Cl. 36—22)

The present invention relates to shoes.

More specifically, the invention relates to insoles for shoes of the Goodyear welt type which, as in common practice, embody a lip cut from the material of the insole and to which the welt and upper of the shoe are secured by suitable stitching.

In welt shoes as at present constructed the insoles include a lip or shoulder projecting downwardly from the sole inward of the margin thereof and extending around the insole from points adjacent the forward edge of the heel. In such insole constructions the space within the lip from adjacent the shank of the insole to the toe thereof is filled with a plastic composition which, when dry, becomes hard and firm.

While these insoles well satisfy the requirements of foundations for shoes of the welt type, nevertheless they have been found objectionable from the standpoint of flexibility and comfort of the shoes, due to the substantial rigidity of the insoles arising from the continuous marginal lip, the hard composition filler, and the imperforate insole body.

Accordingly, a primary object of the present invention is the provision of an insole construction for welt shoes, whereby the above noted objections are overcome.

Other objects and advantages of the invention will become apparent as the description progresses.

The invention will now be described in connection with the accompanying drawing, wherein is disclosed a preferred embodiment of the improved insole construction, and wherein like reference characters designate like parts.

In the drawing,

Figure 1 is a bottom perspective view of a preferred form of my insole construction, the lining and filler being omitted in this view;

Figure 2 is a bottom plan view of the completed insole; and

Figure 3 is a transverse section through a shoe at a position indicated by line 3—3 in Figure 2 and showing the relation between my improved insole, the outsole, welt, and upper.

Referring to the drawing, the letter A designates my improved insole which is constructed from any suitable material and which includes a body portion 10 which, as in usual practice, is provided with a lip 11 adjacent the margin thereof. The lip may be provided in any desired manner, but preferably by cutting the body portion 10 on each side of the lip, turning the cut off portions outward and cementing them together.

In order to render the completed insole highly flexible and to provide in cooperation with the other associated elements a shoe of maximum comfort the insole is completed as follows. The body portion 10 intermediate the shank and toe thereof and preferably at a position adjacent the ball of the foot of a wearer is provided with a multiplicity of perforations 12 which may be of various sizes and which are relatively close to provide maximum flexibility. Furthermore, 10 the lip 11 is slashed at each side of the insole opposite the perforations as is indicated at 13 to create a hinged effect and whereby the lip will not interfere with the desired flexibility as it has in prior constructions.

The insole within the confines of the lip 11 is provided with a suitable fabric reinforcing 14, and the space within the lip from adjacent the shank to the toe is filled with a felt layer 15 which replaces the hard and firm plastic composition heretofore employed in insoles of this type.

The improved construction herein disclosed provides an insole which possesses maximum flexibility adjacent the ball of the foot of a wearer, and the function of such insole as a foundation 25 for Goodyear welt shoes is maintained, as can readily be seen upon inspection of Figure 3.

In said Figure 3 my improved insole is illustrated in a completed Goodyear welt shoe and wherein, in accordance with usual practice, the 30 shoe upper U and the welt W are stitched to the lip 11, whereupon the outsole O is stitched to the welt W.

Thus it will be seen from Figure 3 that the improved insole will not only provide a highly 35 flexible shoe, but, in addition thereto, the felt filler 15 disposed between the insole and the outsole will provide a substantial cushion and the apertures 12, together with the felt layer 15, will provide ventilation whereby maximum comfort 40 will be experienced by wearers of shoes constructed in accordance with my invention.

It is to be understood that the form of my invention herein disclosed is to be considered as a preferred example of same and that various 45 changes may be resorted to without departing from the spirit of the invention or the scope of the subjoined claims.

What I claim and desire to secure by United States Letters Patent is:

1. A welt shoe construction comprising an insole provided with a lip, an upper secured to the insole, and an outsole, a flexible and yieldable filler between the insole and the outsole, a multiplicity of perforations in the insole in an area 55

thereof adjacent the ball of the foot of a wearer, and a plurality of slashes in the lip at opposite sides of the perforated area.

5 2. An insole for welt shoes comprising a body portion having a lip projecting downwardly adjacent the margin thereof, a multiplicity of perforations in the body portion intermediate the shank

and toe thereof, a plurality of slashes in the lip at opposite sides of the perforations, and a flexible filler disposed within the confines of the lip and extending from the shank to the toe of the body portion.

WILLIAM H. GOODYEAR.
